Primary Examiner — Janice Hallmark(74) *Attorney, Agent, or Firm* — McGarry Bair PC(57) **CLAIM**

The ornamental design for a ceiling fan motor housing and light kit combination, as shown and described.

DESCRIPTION

FIG. 1 is a top perspective view of a ceiling fan motor housing and light kit combination showing my new design; FIG. 2 is a bottom perspective view thereof;

FIG. 3 is a top view thereof;

FIG. 4 is a bottom view thereof; and,

FIG. 5 is a side view thereof.

Portions of the drawings shown in broken lines illustrate environmental subject matter and form no part of the claimed design.

1 Claim, 5 Drawing Sheets(56)
